UNITED STATES PATENT OFFICE.

THURE E. DAHL, OF NEW YORK, N. Y.

DESIGN FOR A SOCKET COVER FOR LIGHTING FIXTURES.

Application filed July 21, 1921. Serial No. 486,586. Term of patent 3½ years.

To all whom it may concern:

Be it known that I, THURE E. DAHL, a subject of the King of Sweden, and resident of New York, in the county of New York and State of New York, have invented a certain new, original, and ornamental Design for a Socket Cover for Lighting Fixtures, of which the following is a specification, reference being had to the accompanying draw-

ing, forming part thereof.

The figure is a perspective view of a socket cover for lighting fixtures, showing my new design.

I claim:

The ornamental design for a socket cover for lighting fixtures, as shown.

THURE E. DAHL.
